UNITED STATES PATENT OFFICE

GEORGE H. PERKINS, OF WELLESLEY, MASSACHUSETTS, ASSIGNOR TO POWDRELL & ALEXANDER, INC., OF BOSTON, MASSACHUSETTS, A CORPORATION OF MASSACHUSETTS

DESIGN FOR A TEXTILE FABRIC

Application filed June 10, 1931. Serial No. 40,151. Term of patent 3½ years.

To all whom it may concern:

Be it known that I, GEORGE H. PERKINS, a citizen of the United States of America, residing in Wellesley, in the county of Norfolk, and Commonwealth of Massachusetts, have invented a new, original, and ornamental Design for Textile Fabric, of which the following is a specification, reference being had to the accompanying drawing, forming part thereof.

The figure is a face view of the fabric.

I claim:

The ornamental design for a textile fabric as shown.

Signed by me at Danielson, in the county of Windham and State of Connecticut, this 27th day of May 1931.

GEORGE H. PERKINS.
